UNITED STATES PATENT OFFICE.

RAY P. HIGBEE, OF EDGEWOOD, PENNSYLVANIA.

TRANSFORMER.

Application filed July 10, 1926. Serial No. 121,536.

My invention relates to magnetizable structures, such as transformers, and it has particular relation to an apparatus of this character for impressing a variable voltage upon a receiving circuit.

One object of my invention is to provide a device of the character set forth having portions adapted for relative translatory motion.

Another object of my invention is to provide a magnetizable structure having a plurality of projections, together with means operable at will to magnetically bridge relatively varying portions of the projections.

More specifically stated, it is an object of my invention to provide a structure of the class in question having a plurality of aligned projections, together with a slidable magnetizable member for variably bridging or linking selected numbers of such projections.

20 A further object of my invention is to provide an apparatus of this character embodying a main coil and a plurality of other coils extending substantially at right angles to the first coil for severally or jointly embracing a slidable magnetizable member.

Viewed from another angle, it is an object of my present invention to provide a magnetizable structure having a plurality of partially closed magnetic circuits, together with means operable at will to magnetically close only selected circuits to thereby variably energize a certain coil.

Other and more specific objects of my invention will become evident from the following detailed description, taken in conjunction with the accompanying drawings, wherein

40 Figures 1 to 3, inclusive, are views, in elevation, of a transformer structure embodying my present invention, various positions of the slidable magnetizable member being shown in the respective figures.

Figs. 4 and 5 are views, respectively in side elevation and in section along line V—V of Fig. 4, of the apparatus shown in the preceding figures, together with power-operated means for controlling the slidable member.

50 Figs. 6 and 7 are diagrammatic views illustrating the preferred circuit connections that are employed in connection with the present invention, and

Fig. 8 is a diagrammatic view illustrating a modified form of the present invention as applied to a three-phase circuit.

55 Referring to the drawings, the structure here shown comprises a main magnetizable

core or body member 11 having a plurality of projections or legs 11^a, 11^b and 11^c, with which is associated a slidable magnetizable member or armature 12. A main primary coil or winding 13 is wound around the middle leg or projection 11^b, while an auxiliary primary coil 15 and a secondary coil 14 are disposed at right angles to the coil 13 near opposite sides thereof, and are adapted to selectively embrace the slidable magnetizable member 12. That is to say, the member 12 is adapted to be actuated by any suitable means, as generally indicated by the reference character 16, to pass through the coils 14 and 15, while sliding over the projections 11^a, 11^b and 11^c of the main core member 11.

It will be observed that in Fig. 1 the slidable member 12 occupies its right-hand position, whereby the magnetic circuit between the projections 11^b and 11^c only is closed. In this way the auxiliary coil 15 is fully energized in accordance with the voltage ratio between that coil and the main primary coil 13, whereas the secondary coil 14, inasmuch as its magnetic circuit extending between projections 11^a and 11^b is open-circuited, that is to say, since only an air core is provided for the coil 14, substantially no voltage will be induced therein.

As the slidable member 12 is actuated toward the left to the position shown in Fig. 2, the amount of flux threading the coils of secondary winding 14 increases; while, in the position shown in Fig. 3, in which the slidable member 12 occupies a left-hand position, the coil 14 develops an electromotive force corresponding to the ratio of its turns to those of the primary winding 13, and the auxiliary coil 15 is energized only at a very low value, inasmuch as only a small portion of the armature 12 is included within it.

If desired, the slidable armature 12 may, of course, be so far removed from either of the coils 14 and 15 that substantially no voltage is developed therein, whereas either full voltage or partial voltage may be developed in the other coil, depending upon the position of the armature 12 with respect thereto.

In this way it will be seen that the voltage of secondary winding 14 may be gradually increased from a substantially zero value to a value corresponding to the full ratio of its turns to the turns of the primary winding 13. In order to reduce the magnetizable or no-load current to a minimum value, primary windings 13 and 15 are connected in series re-

lation, as illustrated in Figs. 6 and 7, in such a manner that their induced voltages will add. Consequently, my transformer structure operates with a relatively small magnetizing current and power loss when connected in circuit without load and, when loaded, will provide any voltage desired, from substantially zero to the normal or rated secondary voltage of the transformer.

10 Performance and characteristics of my transformer will compare closely at full voltage with that of a standard transformer of similar dimensions. While the field of application of such a transformer is relatively great, it is particularly adapted to the following uses:

1. Starting any type of alternating-current motor, in which case it may replace both the transformer and the starter that are 20 usually employed.

2. Switching of electric circuits under conditions where arcing and burning is especially undesirable or dangerous.

3. Operating variable speed alternating-current motors and providing smooth acceleration and speed changes.

4. Reducing the no-load or magnetizing current losses.

A plurality of shading coils 20 may be provided in the lower face of the magnetizable member 12 to prevent the magnetic attraction between the armature 12 and the projections of the core 11 from being reduced to a relatively low value.

35 Figs. 4 and 5 illustrate a mechanical arrangement for readily effecting a sliding movement of the armature 12, which arrangement will be of particular value in connection with relatively large transformers where 40 hand operation is inconvenient or otherwise undesirable.

A plurality of wearing strips or ball races 21 may be respectively inserted in the lower face of the armature 12 and the upper faces of 45 the projections 11^a, 11^b and 11^c, and a plurality of balls or rollers 22 are interposed between the strips to thus constitute a ball-bearing or other anti-friction bearing for the 50 sliding member 12 and relieve part of the pressure between armature 12 and core 11. On either side of the core 11 a plurality of vertically-disposed helical springs 23 are positioned to press upwardly against the lower strip 21 or its equivalent, thereby further decreasing the effective pressure or magnetic 55 attraction of the magnetizable armature 12 in accordance with the scale, or adjustment, of the spring members.

The magnetizable armature 12 may be directly associated with a bifurcated member 24, which has a screw-threaded portion that is adapted to extend through a suitable bearing or sleeve 25, which is rotatably mounted upon suitable pedestals or standards 26. The 60 bearing 25 is suitably secured to a gear-wheel

27, which is located between the pedestals 26 and is adapted to be driven by a pinion 28 that is attached to the shaft of a driving motor 29, which may be controlled in any suitable manner. The hub of gear-wheel 27 is 70 internally threaded to engage the threaded portion of member 24.

In this way, by suitable reversal and speed control of the motor 29, the slideable armature 12 may be actuated to any position that is 75 desired, the internally threaded hub of gear-wheel 27 acting as a traveling nut to propel the screw-threaded member 24 and the armature 12 in the desired direction and to the desired extent.

80 Referring to Fig. 8, the structure therein shown comprises a three-phase variable-voltage type of transformer embodying, in general, a stator or outside ring 31 and an internal cylinder or inductor rotor 32, which is 85 suitably supported upon a shaft or axle 30. The inner surface of the ring 31 is provided with a plurality of projections or poles (in this case, eighteen) which are arranged in sets, respectively numbered 33^a, 34^a and 35^a, 90 33^b, 34^b and 35^b, etc., to correspond to the phases of the circuit. The cylinder or rotor 32 is provided with a materially smaller number of larger projections or segments 36 (in this case, six), which are thus adapted to magnetically bridge two or three of the projections of the ring 31 in accordance with the position of the rotor. Each segment 36 has an angular width equal to the stator pole pitch (20°).

100 Suitable windings are distributed symmetrically around the projections of the stator 31, in order to provide a perfect mechanical and electrical balance. Circuits for one phase only are shown in the figure for the sake of simplicity and clearness. It will be noted that the windings on poles 33^a and 35^a are connected in series relation between the phase terminals 37 and 38 of the power supply and these windings respectively correspond, for one phase, to the primary winding 13 and the secondary winding 15 of the previously illustrated type of transformer. The windings on the poles 34^a form part of the secondary circuits of the transformer 110 and are adapted to supply a variable voltage to the secondary terminals, such as 39 and 40. With the inductor armature in the position shown, the iron circuit through poles 34^a is not closed and the secondary voltage, due 120 to windings on these poles, will be practically zero.

The inductor segments 36 close the iron circuits through each pair of poles 33^a and 35^a. Since the windings on each pair of these poles are connected in series relation, in such manner as to add their voltages, the voltage on the main primary winding will be reduced by the voltage drop, due to the windings on poles 35. In this way the no-load power 130

losses of the transformer may be materially reduced, as previously explained.

Turning the inductor armature 32 to an angle equal to the pole pitch will transfer the closed iron magnetic circuit from poles 33^a and 35^a to poles 33^a and 34^a. The voltage consumed in the windings on poles 35^a will decrease to a low value since the iron magnetic circuit through these poles is not now closed. On the other hand, the voltage impressed on the main primary windings on poles 33^a will thus be increased to approximately line voltage, while the secondary voltage, due to the windings on poles 34^a, will now be approximately that determined by the transformer ratio. The apparatus shown in Fig. 8 is the preferred form for motor starting purposes.

It will be seen that I have thus provided a relatively simple and effective structure for producing an alternating-current voltage that is variable over a wide range and that the structure has relatively low magnetizing current or no-load losses.

I do not wish to be restricted to the specific circuit connections or arrangement of parts herein set forth, as various modifications thereof may be effected without departing from the spirit and scope of my invention. I desire, therefore, that only such limitations shall be imposed as are indicated in the appended claims.

I claim as my invention:

1. A magnetizable structure having a stationary portion, a second portion adapted for motion past said stationary portion, and coils respectively embracing said stationary portion and at times said second portion.

2. A magnetizable structure having a plurality of projections, means operable at will to magnetically bridge relatively varying portions of said projections, and stationary coils respectively wound on one of said projections and adapted to embrace said means.

3. A magnetizable structure having a plurality of alined projections, means for magnetically bridging various portions of said projections, and coils respectively wound on one of said projections and disposed substantially parallel thereto for receiving said means.

4. A magnetizable structure having a plurality of alined projections, slidable magnetizable means for variably bridging said projections, and a plurality of coils for respectively magnetizing said structure and at times embracing said means.

5. A magnetizable structure having a plurality of projections, a magnetizable member for linking selected numbers of said projections, and a plurality of coils for respectively embracing various portions of said member.

6. A magnetizable structure having a plurality of projections, a magnetizable member for linking predetermined pairs of said pro-

jections, a coil wound on said structure, and a plurality of other coils for severally or jointly embracing said member.

7. A magnetizable structure having a plurality of projections, means for magnetically close-circuiting and open-circuiting selected projections, a coil wound on one of said projections, and a plurality of other coils for severally or jointly embracing said member. 70

8. A magnetizable structure having a plurality of alined projections, a slidable magnetizable member for linking selected numbers of said projections, and a plurality of coils extending parallel to said projections for respectively embracing various portions 80 of said member. 75

9. A magnetizable structure having a plurality of alined projections, a slidable magnetizable member for linking predetermined pairs of said projections, a coil wound on said structure, and a plurality of other coils extending substantially at right angles to the first coil for severally or jointly embracing said member. 85

10. A magnetizable structure having a plurality of alined projections, a slidable member for magnetically close-circuiting and open-circuiting selected projections, a coil wound on one of said projections, and a plurality of other coils extending at an angle to 90 the first coil for severally or jointly embracing said member. 95

11. A magnetizable structure having a plurality of partially closed magnetic circuits, a plurality of inductively related coils associated therewith, and means operable at will 100 through one of said coils to magnetically close only selected circuits to thereby variably energize said coil.

12. A magnetizable structure having a plurality of partially closed magnetic circuits, a coil for energizing said circuits, a plurality of other coils inductively related to the first coil, and magnetizable means operable into 105 one of said other coils for closing only selected circuits to thereby variably energize that coil. 110

13. A magnetizable structure having a plurality of partially closed magnetic circuits, a coil for energizing said circuits, a plurality 115 of other coils inductively related to the first coil, and slidable magnetizable means operable through one of said other coils for closing only selected circuits to thereby variably energize that coil. 120

14. A magnetizable structure having a plurality of partially closed magnetic circuits, a coil for energizing said circuits, a plurality of other coils inductively related to the first coil, and magnetizable means operable 125 through said other coils for closing only selected circuits to thereby variably energize one of said other coils, the first coil and one of the others being connected in series relation. 130

15. A magnetizable structure having a plurality of partially closed magnetic circuits, a coil for energizing said circuits, a plurality of other coils inductively related to the first coil, and magnetizable means for closing only selected circuits to thereby variably energize one of said other coils, the first coil and one of the others being conductively connected in cumulative voltage relation. 25
- 10 16. A magnetizable structure having a plurality of partially closed magnetic circuits, a coil for energizing said circuits, a plurality of other coils inductively related to the first coil, and slidable magnetizable means for closing only selected circuits to thereby variably energize one of said other coils, the first coil and the remaining coil being conductively connected in additive voltage relation. 30
- 15 17. A magnetizable structure having a plurality of alined projections, means for mag- 35
- netically bridging various portions of said projections, and means for varying the pressure of said means upon said projections.
18. A magnetizable structure having a plurality of alined projections, a magnetizable member, means for sliding said member over said projections, and spring means for supporting part of the pressure of said member.
19. A magnetizable structure having a plurality of alined projections, a magnetizable armature, ball bearings interposed between said armature and said projections, a travelling screw and nut associated with said armature, a motor geared to said nut, and a plurality of springs for supporting a portion of the pressure of said armature.

In testimony whereof, I have hereunto subscribed my name this 9th day of July 1926.

RAY P. HIGBEE.
